UNITED STATES PATENT OFFICE.

WILLIAM L. CANNIFF, OF NEW YORK, N. Y.

PNEUMATIC GROUT MIXING AND DISCHARGING APPARATUS.

No. 873,345.

Specification of Letters Patent.

Patented Dec. 10, 1907.

Application filed October 29, 1906. Serial No. 841,042.

To all whom it may concern:

Be it known that I, WILLIAM L. CANNIFF, a citizen of the United States, residing in the borough of Manhattan, city, county, and 5 State of New York, have invented certain new and useful Improvements in Pneumatic Grout Mixing and Discharging Apparatus, of which the following is a specification.

The object of my invention is to effect the 10 admixture of the constituent parts of grout in a more simple, rapid and effective manner than heretofore, at the same time dispensing with mechanical mixers, motors and the like, and rendering the operation essentially automatic in character. Mechanical mixers, 15 with their motors and other essentials are relatively expensive in the first place, necessitate the use of skilled labor, and even with the best of care and attention, need, owing to 20 the gritty character of the material treated, almost constant repair and replacement of parts, so that the expense of running and maintenance is burdensome and detracts materially from their value and utility. I ob- 25 viate these objections by dispensing entirely with operative parts in the sense that I effect the admixture of the grout without the aid of mechanical beaters, arms or agitators, by means of compressed air. Furthermore, the 30 admixture of elements is more uniform and perfect, and is accomplished in much less time than heretofore.

The invention consists primarily in injecting compressed air into the aggregated material, as sand, cement and water, in such manner that the air in expanding passes through the same, thoroughly agitating and admixing the ingredients by a process which may be designated as "boiling" or analogous 40 thereto. As a result, a uniform blending and distribution of the component parts of the mass is quickly attained; after which compressed air is further utilized to effect the discharge of the admixture as heretofore. 45

My invention also includes certain specific features in the construction and arrangement of parts hereinafter described and claimed.

In the accompanying drawings, Figure 1, 50 is a plan of a mixing chamber and connections embodying the essential features of my invention; Fig. 2, is a sectional elevation taken upon plane of line 2—2—Fig. 1; Fig. 3, is a plan in detail of the underside of the 55 vent shield; Fig. 4, an edge view of the vent shield; Fig. 5, is a plan of the deflector; Fig.

6, a side elevation thereof; Fig. 7, is a horizontal section on plane of line 7—7—Fig. 2; Fig. 8, is a horizontal section on plane of line 8—8—Fig. 2.

In the practical application of my invention the form or configuration of mixing chamber C is of secondary importance, and I do not limit myself in this respect, neither do I restrict myself to the identical arrangement of parts herein shown, since modifications thereof may be resorted to with like result,—the essential feature in this respect being the use of means whereby compressed air may be forced through the ingredients 70 within the chamber for the purpose set forth.

Obviously a preferable arrangement for practical reasons is to employ a mixing chamber C, the main portion of which is of cylindrical form, and to introduce the compressed air at the bottom of said chamber, so that the air in rising will thoroughly agitate the contents of the chamber. This I prefer to do through the medium of a pipe which is also used as a medium of discharge for the 80 grout after the admixture of the component parts thereof. The lower portion of the chamber C is closed by an inverted conical section e, through the truncated end of which the pipe a, projects. Over the open end of 85 the pipe a, is arranged a deflector d, preferably in the form of an inverted dish shaped plate formed with flanged lugs d', by which it is secured to the conical section e.

b, is an air pipe extending to any suitable 90 source of supply of air under pressure. This compressed air pipe b, enters a three way valve b', communicating through the pipe b², with the upper part of the cylinder C and through the pipe b³, with the combined air 95 inlet and grout discharge pipe a. The handle b'', of the three way valve b', is formed with a pointer b^x, which indicates the direction of air flow when the valve is open,—the valve being shown as in its closed position in 100 the drawings.

e, is a discharge valve controlled by the handle e'.

g, is a transverse grating of any suitable or desired construction inserted in the mixing 105 chamber C to assist in breaking up and disintegrating any lumps of cement or sand inadvertently introduced into the chamber C. As shown in the drawings the grating consists of three zig zag strips of flat metal 110 placed edge-wise with relation to the vertical axis of the cylinder C, with ample space be-

tween their opposed surfaces for the passage of the contents of the chamber in either direction, as will be seen by reference to Fig. 7.

The ingredients of the grout are introduced 5 into the mixing chamber C through the opening c', closed preferably by a swinging door c², opening inward and provided with a gasket c³, for forming an air tight joint when the door is closed,—the door being held by internal pressure in use.

c⁴, c⁴, are angle beams on the exterior of the cover adjoining the door opening c', and are designed to stiffen and reinforce the edges of said openings so as to insure a close seal 15 with the gasket c³, on the door c².

V is a vent pipe provided with a stop cock v,—the inner end of the vent pipe being protected by a screen s, which admits of the escape of air while intercepting and deflecting 20 any of the grout mixture that might otherwise pass to the vent.

Attached to the discharge valve e, is a flexible pipe d'', through and by which the mixed grout is distributed.

25 The operation is as follows. The valves b' and e, being closed, the material is introduced through the opening c', the cock v, in the vent tube V opened, the door c², closed, and the valve b', turned with the pointer b^x 30 downward, admitting compressed air to the chamber C, and thereby sealing the door c², by excess of internal pressure. As the compressed air escapes from the pipe a, it expands and rises, being deflected by the inverted plate d, through the grout material, 35 violently agitating the latter and causing a state of ebullition which results in a thorough and uniform admixture of the ingredients. During this action air escapes around the 40 edges of the shield s and through the vent V. A fraction of a minute (about 30 seconds in fact) is sufficient to insure a thorough blending and distribution of the ingredients to form the grout by this method of "boiling"

45 or agitation, when the valve v, may be closed and the valve b', reversed to shunt the compressed air into the top of the cylinder C, when the valve e, being opened, the grout is discharged by displacement by the pressure 50 and accumulation of compressed air above it in the mixing chamber. In this connection, I wish to state that I am aware that compressed air has been used to force grout from a mechanical mixer, but I am not aware that 55 compressed air has heretofore been employed to agitate and mix the ingredients as a preliminary to such discharge.

It will be seen that my apparatus is extremely simple and inexpensive, there being 60 no operative parts, and nothing to get out of order. Practically the device cleans and lubricates itself in action, and may be used effectually by unskilled labor. Furthermore it is of light and portable structure, a feature 65 of special importance in the art to which it

appertains as will be readily understood, since it can be transported to the immediate vicinity of the place where the grout is to be applied, and the grout formed and applied direct while fresh and in the best condition. 70 I thus not only save time in the preparation of the grout, but also in handling and manipulation. I have found by practical experience that by my method the materials may be more thoroughly and satisfactorily mixed 75 in one third the time involved in the use of the mechanical mixers, which it is designed to replace, while the cost of my apparatus is comparatively speaking, merely nominal, and the cost for repairs is practically eliminated. 80

What I claim as my invention and desire to secure by Letters Patent is,

1. In a device of the character designated, the combination of a mixing chamber, means 85 for introducing material to be mixed into said chamber, means for sealing said chamber, and means connected with said chamber for injecting compressed air therein below the material contained therein for the purpose of mixing the same.

2. In a device of the character designated, the combination of a mixing chamber, means 90 for introducing materials to be mixed in said chamber, means for sealing said chamber, means connected with said chamber for injecting compressed air therein below the material contained therein for the purpose of mixing the same, and an air vent and vent valve connected with said chamber, for the 100 purpose described.

3. In a device of the character designated, the combination of a mixing chamber, means 105 for introducing materials to be mixed in said chamber, means for sealing said chamber, means connected with said chamber for injecting compressed air therein below the material contained therein for the purpose of mixing the same, and means for discharging said chamber of its contents by air pressure 110 for the purpose described.

4. In a device of the character designated, the combination of a mixing chamber, means 115 for introducing materials to be mixed in said chamber, means for sealing said chamber, means connected with said chamber for injecting compressed air therein below the material contained therein for the purpose of mixing the same, an air vent and vent valve connected with said chamber, and means for discharging the mixed material by air pressure 120 for the purpose described.

5. In a device of the character designated, the combination of a mixing chamber, means 125 for introducing materials to be mixed in said chamber, means for sealing said chamber, means connected with said chamber for injecting compressed air therein below the material contained therein for the purpose of mixing the same, an air vent and vent valve 130

connected with said chamber, and a shield in said chamber opposed to and protecting said vent for the purpose described.

6. In a device of the character designated, 5 the combination of a mixing chamber having an inverted conical bottom, a pipe entering the truncated end of said conical bottom and connected with a discharge pipe and with a compressed air pipe, a compressed air pipe 10 entering the upper portion of said mixing chamber, valves controlling said pipe, means for introducing materials to be mixed in said chamber and means for sealing said chamber, for the purpose described.

15 7. In a device of the character designated, the combination of a mixing chamber, means for introducing materials to be mixed in said chamber, means for sealing said chamber from within, means connected with said 20 chamber for injecting compressed air through the bottom thereof to mix the materials and means for discharging said chamber of its contents by air pressure, for the purpose described.

25 8. In a device of the character designated, the combination of a mixing chamber, means for introducing materials to be mixed in said chamber, means for sealing said chamber from within, a pipe entering the bottom of 30 said chamber, means for introducing compressed air through said pipe to mix the materials and means for introducing compressed air into the upper portion of said chamber, for the purpose of discharging the contents 35 thereof.

9. In a device of the character designated, the combination of a mixing chamber, means for introducing materials to be mixed in said chamber, means for sealing said chamber, a 40 pipe entering the bottom of said chamber, a deflecting plate opposed to the opening in said pipe, means for introducing compressed air through said pipe to mix the materials and means for introducing compressed air 45 into the upper portion of said chamber, for the purpose described.

10. In a device of the character designated, the combination of a mixing chamber having an inverted conical bottom, a pipe 50 entering the truncated end of said conical bottom, connecting with a discharge pipe and with a compressed air pipe, an inverted dish shaped deflector plate opposed to the opening in said pipe, a compressed air pipe 55 entering the upper portion of said mixing chamber, valves controlling said pipe, means for introducing materials to be mixed in said chamber and means for sealing said chamber, for the purpose described.

60 11. In a device of the character design-

nated, the combination of a mixing chamber, a discharge pipe and a pipe for conducting compressed air into said chamber a pipe entering the bottom of said mixing chamber and connecting with said discharge pipe and said 65 compressed air pipe, said compressed air pipe also connecting with the upper portion of the chamber, a three way cock in said compressed air pipe and a valve in the discharge pipe, for the purpose described. 70

12. In a device of the character designated, the combination of a mixing chamber having an inverted conical bottom a discharge pipe, and a pipe for conducting compressed air into said chamber a pipe entering 75 the truncated end of said conical bottom and connected with said discharge pipe and with said compressed air pipe, said compressed air pipe also entering the upper portion of said chamber, a three way valve in said compressed air pipe, a valve in the discharge pipe, a vent valve communicating with the upper part of the chamber and an inverted dish shaped deflector opposed to the opening in the pipe, which enters the truncated end 80 of the conical bottom, for the purpose described.

13. In a device of the character designated, the combination of a mixing chamber, means for introducing compressed air into 90 the bottom of said mixing chamber, a grating extending transversely across said chamber above the bottom thereof, means for introducing materials to be mixed into said chamber, means for sealing said chamber and 95 means for discharging the contents of said chamber by air pressure, for the purpose described.

14. In a device of the character designated, the combination of a mixing chamber 100 having an inverted conical bottom a discharge pipe, and a pipe for delivering compressed air into said chamber a pipe entering the truncated end of said conical bottom and connected with said discharge pipe and with 105 said compressed air pipe, a compressed air pipe entering the upper portion of said mixing chamber, valves controlling said pipe, a transverse screen in said mixing chamber consisting of a series of flat metal bars arranged with their edges parallel to the longitudinal axis of the chamber, means for introducing materials to be mixed into said chamber and means for sealing said chamber, for 110 the purpose described.
